UNITED STATES PATENT OFFICE

EDWIN A. RUTENBER, OF MILWAUKEE, WISCONSIN, ASSIGNOR TO A. J. LINDEMANN & HOVERSON COMPANY, OF MILWAUKEE, WISCONSIN, A CORPORATION OF WISCONSIN

THERMOSTATIC DEVICE

Application filed September 18, 1926. Serial No. 136,234.

The improvements relate to thermally operated devices for controlling the temperature of ovens and the like, and are primarily intended to be used in connection with electrically heated ovens, but have other applications. Their objects are, among others, to improve the construction and arrangement of the parts, including the heat responsive member, switch and visible indicator and their connections, rendering the same more efficient, durable and dependable and strengthening and simplifying the construction and the assembling thereof; to protect the parts against accidental injury in use, and to locate them at such a part of the oven or the like and arrange them in such a manner that they will be more convenient to the operator and user.

The improvements are illustrated in the accompanying drawings, in which

Fig. 1 is a front view of a corner of an oven frame with thermostatic device embodying the improvements mounted therein;

Fig. 2 is a side view thereof with the protecting cover for the switch and connections removed;

Fig. 3 is a vertical cross section on the line 3—3 of Fig. 2 looking in the direction indicated by the arrows in that figure;

Fig. 4 is a perspective of the case or housing in which the operating parts are mounted and by which they are protected.

The thermostatic device or temperature control of the present improvements is designed to be set in or built into the side of the oven, with the indicator for controlling and indicating the temperature projecting through the front frame of the range and covered by a curved plate having therein a window or sight of transparent material through which the indicator and the scale may be observed. The construction of the operating parts is similar to that shown and described in the co-pending application of Lindemann and Rutenber, filed October 10, 1924, Serial Number 742,748, which shows a tube containing a globule of conductive material mounted on one end of an oscillatory shaft to rock therewith, the shaft rotating in a rotatable bearing, to the other end of which is attached the free end of a spiral or coil of

thermostatic metal, the opposite end of said coil being fastened to the rotatable bearing which has mounted thereon an indicating lever connected therewith by frictional means permitting adjustment. The said application is therefore referred to for illustration and description of details of construction not herein fully set forth. 55

In the drawings, 1 represents the front plate of the oven and range, 2 the outer side plate thereof, 3 the top plate or cover, and 4 the inner wall of the oven which is spaced from its outer walls to provide the usual heat insulating chamber of a double oven. On the front plate is fixed the segmental cover 65 plate 5 with a curved window 6 therein, and having a chord slot 7 in its side through which the small handle 9 of the indicator projects and in which it moves. The scale 8 is secured to the front oven plate and has 70 numbers and graduations thereon to indicate temperatures. The scale plate is also curved substantially on the arc of the indicator, as is also the outer part of the cover 5, the window 6 and slot 7, and this insures accuracy 75 of indication enabling the pointer to pass over the scale in close proximity thereto.

The handle 9 and indicator 10 are fixed to the end of an arm 11 in turn fixed to the annular flange 13 on the sleeve 12 so that the 80 said sleeve can be rotated thereby in its fixed tubular bearing 14 and the thermostatic helical band 15 turned to a limited extent thereby by reason of the fixed connection 16 between the inner end of said sleeve and the 85 said helical band. This thermostatic element may have the form shown or any other desired form, and may be made of any material suitable for the purpose.

To the opposite end of the band 15 the inner end of the shaft 17 is fixed, as indicated at 18, so that when the band turns the shaft is rocked, and the vessel 19 mounted in fixed relation thereto on its opposite end, by means of the metal strap 20 and clamping nut 21 is 90 tilted therewith. The vessel is of glass or other non-conductive material and has therein a globule 22 of conductive material normally in one end thereof and in contact with the terminals 23 and 24 of the electric con- 100

ductors 25 and 26 to close the circuit which energizes the heating unit. When the coil 15 expands under the influence of heat it rotates the shaft 17 counterclockwise (Fig. 2) and causes the vessel to move in the same direction to and beyond horizontal position, so that the globule will gravitate to the other end of the bottle and break the circuit. The globule is preferably mercury, but may be 10 made of any other material, having any consistency, and adapted to gravitate in the vessel, suitable for the purpose. It will be seen, therefore, that when the arm 11 is moved upward the bottle is canted to a greater degree, and a greater torsion of the band 15, requiring a greater degree of heat, will be necessary to rock it to and beyond horizontal position and break the circuit. In order to adjust the instrument to the oven in connection with which it is used so that the readings of the scale will be accurate a toothed disk 27 is mounted on the shouldered end of the sleeve 12, and forms the connection between the annular flange 13, carrying the arm, and the sleeve, the said flange being actually an annular ring set on the sleeve. To adjust the arm 11 therefore with respect to the sleeve it is only necessary to loosen the set screw 28, in fixed relation to the former, thus disconnecting 20 the two and to move the arm to the desired extent, then tighten the screw and secure it in position. In this simple manner the instrument may be calibrated when it is assembled and mounted in the oven, or at any 30 other time. It will be understood that the toothed disk or ring 27 is fixed to the sleeve 12.

The housing for the switch, arm and their connections is in the form of a hollow casting 40 (Fig. 4) with a central opening 30 in which the tubular housing 14 is threaded, an opening 31 through which the conductor wires may be passed and screw holes 32 and 33 to receive fastening means whereby it is attached to the outer side plate and the front plate respectively of the oven. The protecting cage 34 for the thermostatic coil 15 is threaded on the inner end of this housing. To assemble the instrument, therefore, it is 50 only necessary to pass it through the large opening 2' in the side plate, pass screws through the holes 2" and through the holes 32 and then place the cage in position from the inside of the oven. This enables the 55 manufacturer to assemble the instrument before it is applied to the oven. The arm 11 is passed through the opening 1' in the front plate before the indicator plate and the parts carried thereby are attached, and secured to the extension 13' of the flange 13 by means of set screws 11'. The scale plate 6 is then secured to the front plate and the curved cover 5 placed over it, the slot 7 being passed over the handle 9 in this operation, and the said 65 cover then secured to the oven front. The

cover 35 is secured to the side of the oven by the same screws which secure the housing 29, but may be removed without disconnecting the housing because the latter is also secured to the front plate of the oven. Therefore, 70 the plate 35 may be removed and replaced, and access to the instrument obtained thereby without disconnecting any other part.

I claim:

1. In combination with a heating chamber 75 having inner and outer walls spaced apart, a thermostatic device for controlling the generation of heat in said chamber having a temperature responsive element therein and switch and control mechanism mounted between said walls, the outer of said walls having an opening to permit the insertion and removal of said switch mechanism and element, a removable cover for said opening, a rigid housing supporting said switch, element and control positioned between said walls and forming therewith an enclosure for said switch and control.

2. In a thermostatic temperature control device, the combination with a heating compartment, of a heat operated element in said compartment, electric conductors for a current to operate heating means for said compartment, a switch operatively connected with said element and arranged to be operated thereby to interrupt the current passing through said conductors and means for varying the operative relation between said switch and said element extending away from the same to a point exterior to said compartment, a housing within the outer walls of said compartment receiving said switch and varying means and fixed means for indicating the extent of such variation located exterior to said compartment, said compartment having multiple walls spaced apart, said switch being located between said walls with said varying means and said indicator means being positioned exterior to said walls.

3. In combination with a heating compartment having inner and outer walls spaced apart, a helical thermostatic member disposed in said compartment, a rotatable sleeve extending through said inner wall, a rotatable shaft extending through said inner wall, said sleeve and shaft being connected by said helical member, a circuit maker and breaker within said walls and supported on said shaft, an arm for rotating said sleeve and disposed between said walls, a portion of said arm extending exteriorly of the walls, an indicator scale exterior to said walls with which said arm portion is associated, a disc within said walls fixed to said sleeve, releasable means connecting said disc and arm, and disposed between said walls, said means being releasable for moving said arm relatively to said switch.

4. In combination with a heating com- 130

partment having inner and outer walls spaced apart, a thermostatic member disposed in said compartment, a rotatable sleeve extending through said inner wall, a 5 rotatable shaft extending through said inner wall, said sleeve and shaft being connected by said thermostatic member, a circuit maker and breaker within said walls and supported on said shaft, actuating means including an arm for rotating said sleeve and disposed between said walls, a portion of 10 said arm constituting a pointer, an indicator scale with which said arm portion is associated, a disc within said walls fixed to said 15 sleeve, releasable means connecting said disc and actuating means, and disposed between said walls, said means being releasable for moving said actuating means relatively to said sleeve.

20 Witness my hand this 15th day of September, 1926, at the city of Milwaukee, in the county of Milwaukee, State of Wisconsin.

EDWIN A. RUTENBER.
